UNITED STATES PATENT OFFICE

FRITZ SCHELLHORN, OF PRAG-WEINBERGE, GERMANY, ASSIGNOR TO NIGROLIT-WERKE, G. M. B. H., OF BERLIN-WEISSENSEE, GERMANY, A GERMAN COMPANY

PRESSURE FRAME OR APPARATUS FOR USE IN THE PRODUCTION OF SOUND RECORDS

Application filed November 8, 1928, Serial No. 318,072, and in Germany December 9, 1927.

This invention relates to a pressure frame for record plates or discs, by means of which thin matrices or impressions produced by galvano-plastic means are secured upon a base plate so that they are perfectly even and fixed in position, pressure rings being used for the aforesaid purpose.

In the known constructions of pressure frames of this description, the pressure rings 10 have been attached by means of screws to the overhanging edge of the pressure frame.

This method of attachment involves particular care in handling, since in order that the matrix may lie evenly upon the base plate, an even tension or pull exerted by the screws is necessary, and in addition there must be an even pressure exerted by the pressure ring upon the entire circumference of the matrix or impression plate which is difficult to obtain, even where a large number of equally spaced screws are provided around the circumference.

By means of the pressure frame constructed according to the invention, the attachment of the simple pressure ring is so effected that it is held down evenly around its whole circumference, and so that, without the use of screws this even pressure of the pressure ring is communicated to the base plate, or to the matrix or impression surface.

According to the invention this is effected by constructing the pressure ring as a spring ring, that is to say it is formed so that it is resilient either in the circumferential sense 35 or in cross section, and so that it can be pressed into a groove in the pressure frame, or rolled into the same, which groove is of appropriate arc shaped section, contracted towards the upper part. In this way the ring 40 is pressed downwards over its whole periphery upon the matrix or impression plate, whilst at the same time a stretching of the galvano-plastic element in a radial direction is rendered possible. This is of particular 45 importance at the first pressing. By reason of the resiliency of the pressure ring, the easy and simple removal of the same from the groove in the pressure frame can be effected.

50 The subject of the invention is shown by

way of example in the accompanying drawings, in which:

Fig. 1 is a vertical section of one method of construction.

Fig. 2 is a plan with the pressure ring removed. 55

Fig. 3 is a plan with the pressure ring inserted.

Figs. 4 and 5 show respectively in section and in plan a second constructional embodiment of the invention. 60

Referring to Figs. 1 to 3, the pressure frame includes a strong base plate 1 having a central supporting peg 2 to extend through a central opening in the matrix or impression plate 3 and thereby hold the latter in place. In the neighborhood of its circumference, the base plate 1 is provided with a circular groove 4, the outer wall or surface 5 of which is extended in an inwardly slanting direction or is curved upwards, as shown at Fig. 1. The pressure ring 7 is cylindrical on its inner surface and has a substantially conical portion 6 on its outer surface and is provided with an inwardly extending annular flange 7^a adapted to rest on the matrix, which extends approximately horizontally and at right angles to the part 6. Said pressure ring is formed in the manner of a piston ring, being provided with a break or split 70 75 80

9, Fig. 3, so that it can be forced inwards in a resilient manner but tends automatically to spring outwards into its original form. In this way on being pressed or rolled into the groove 4 of the base plate, the ring rests 85 90 95 resiliently against the outer wall of the groove and is at the same time forced downwards owing to the conical formation of the outer wall 5 of the groove 4 and at the same time is pressed around its whole periphery in such a way that it presses with uniform pressure upon the matrix 3 by means of the circumferential flange 7.

In the constructional embodiment illustrated at Figs. 4 and 5, the pressure frame 1 is provided with two circumferential grooves 10 and 11. The inner circular groove 10 is formed at its outer wall 12 so that it is of circular arc shape in cross section. The outer groove 11 may be of any appro- 100

priate shape. It is simply intended for the reception of material extruded during the pressing from the pressure mass or material.

The cross section of the pressure ring 7 in the constructional embodiment according to Figs. 4 and 5 includes two substantially S shaped adjacent circular arc shaped portions 6a, 6b, of which the first is flattened at its end. By this formation of the ring it is rendered resilient in itself, and by its resilience can be easily pressed into the circular groove 10 whilst remaining perfectly tight against the wall 12 of the groove 4 and pressing simultaneously in a springy manner upon the matrix 3, so that the extrusion of pressed material between the seating of the pressure ring and the matrix is prevented.

13 is a perforation through which a gentle push can be exerted from below upwards.

20 What I claim and desire to secure by Letters Patent of the United States of America is:—

25 1. A pressure frame for the production of disc records, comprising a base plate having an annular groove in its upper side, the outer wall of which groove is hollow, and a resilient pressure ring, having a flange on its inner periphery to bear on and around the edge of a matrix plate on said base plate and 30 also having annular portion to enter said groove, said annular portion having a convex outer periphery to snap, by the resilience of the said pressure ring into engagement with the said hollow outer wall.

35 2. A pressure frame or device according to claim 1, wherein the pressure ring is formed as a complete ring substantially S shaped in cross section and in which the groove is provided with a wall having an 40 arc shaped curve into which the ring is adapted to be sprung.

45 3. A pressure frame or device according to claim 1, wherein the frame is provided beneath the groove for the reception of the pressure ring with at least one perforation for the purpose of pushing the ring out of the groove from beneath.

In witness whereof I affix my signature.
FRITZ SCHELLHORN.
